UNITED STATES PATENT OFFICE.

HARRY A. DOUGLAS, OF BRONSON, MICHIGAN.

ELECTRIC SWITCH.

Application filed February 6, 1928. Serial No. 252,278.

My invention relates to electric switches of the class employing stationary contacts and electrically connected spring pressed movable contacts for bringing the stationary contacts and the circuit wires leading thereto into and out of circuit and into and out of various circuit combinations.

Such switches are used, for example, in controlling the circuits of automobile head lamps, the switches, according to their adjustments, causing the head lamps to glow dimly or brightly or to be extinguished. Such switches of the prior art employed metallic spring barrels which were mechanically and electrically assembled by means of floating metallic plates, the spring barrels having their end walls formed to constitute switch contacts which, in riding into and out of engagement with the stationary contacts complementary thereto, would cause the floating metallic plates to assume various angles during their bodily movements with the result that the spring barrels were apt to bind in the contact actuators with which they were intended to have sliding engagement.

In carrying out my present invention, spring barrels are employed as a part of the moving element of the switch but these spring barrels are not formed to serve as contacts which are complementary to the stationary contacts, there being, however, associated with these spring barrels contacts that are complementary to the stationary contacts and which are spring pressed, to function, by means of springs which are housed by the spring barrels. A carrier is provided for the spring barrels, this carrier being pressed into engagement with an abutment by the aforesaid springs whereby this carrier is preferably held in a fixed plane of rotation and with which the spring pressed contacts can not have binding engagement. Said spring pressed contacts are in electrical connection to enable them to bridge the stationary contacts with which they are brought into engagement. In the preferred embodiment of the invention, the electrical connection of the spring pressed contacts is effected through the intermediation of the spring barrels which are of metal and with which the spring pressed contacts have sliding engagement, the spring barrels themselves being directly electrically connected preferably by means of a metallic plate having holes formed therethrough, the portion of the plate main-

gining said holes being tightly received within annular grooves that are formed in the barrels.

In the preferred embodiment of the invention, a casing is employed which has two opposite end walls, the stationary contacts being carried upon one of these walls, which thus constitutes a contact carrier, and exposes within the casing for engagement and which contacts are constructed for electrical connection therewith of circuit wires led to the casing. A handle is provided upon the exterior of the casing and is mounted to turn at the other casing end wall in a plane substantially parallel therewith, this other casing end wall serving as one form of abutment hitherto generally described. A second contact carrier is provided, this second contact carrier being disposed within the casing and coupled with the handle to be turned thereby, this second contact carrier being held from outward movement by the casing end wall at which the handle is disposed and which serves as the abutment that limits the outward movement of the second contact carrier. The spring barrels are coupled with the aforesaid second contact carrier and turned therewith, the contacts which are complementary to the stationary contacts being preferably disposed within the spring barrels, the springs within the barrels pressing these contacts into position to be engageable with the stationary contacts and pressing the aforesaid contact carrier against the end wall at which the handle is disposed and which end wall serves as the abutment. The contacts which are within the spring barrels and are projected therefrom by the springs are brought into electrical connection independently of the stationary contacts by means of such a metallic plate as has hitherto been described and which is carried by the movable contact carrier.

The invention will be more fully explained by reference to the accompanying drawing in which Fig. 1 is a sectional elevation illustrating the preferred embodiment of the invention, parts being shown in full elevation; Fig. 2 is a sectional view on line 2-2 of Fig. 1; Fig. 3 is a view on a smaller scale showing the relationship of various contacts; Fig. 4 is a sectional view illustrating a step in the preferred method of assembling the spring barrels and the contact carrier with which they are assembled; Fig. 5 illustrates a modification of that which is illustrated by Fig. 4;

and Fig. 6 is a sectional view of a modification employing the structural characteristics of Fig. 5.

The casing has a front end wall 1 and a side wall 2, the wall 1 being essentially flat and the wall 2 being preferably cylindrical. The mounting cup 3 is suitably assembled with the end wall 1 as by means of the rivets 4. The end wall 1 serves as an abutment as will 10 more fully hereinafter appear.

The other end wall 5 is preferably in the form of a plate or block of insulation and constitutes a closure for the cup shaped casing 1, 2. The end wall 5 is also a contact carrier, 15 there being contacts that are inclusive of metallic sleeve portions 6 which are provided upon and passed through the wall 5. Said sleeve portions 6 have flanges 7 at their inner ends, these flanges being flush with the inner 20 surface of the casing wall or contact carrier 5 so as to be exposed within the casing for engagement with complemental contacts to be described. The contacts upon the carrier 5 are constructed for electric connection there- 25 with of circuit wires 8 which are led to the casing. As illustrated, the sleeve contact portions 6 are interiorly threaded and receive metallic binding screws 9 which serve to clamp the wires 8 against the flanges 10 which are 30 provided at the outer ends of said sleeve contact portions.

A handle 11 has a circular hub 12 which passes through a circular hole 13 formed in the end wall of the mounting cup 3 and co- 35 axially with the cylindrical casing wall 2. Said hub is formed with two inwardly extending projections 14 and 15 between which the U-shaped stirrup 16 is snugly fitted. A screw 17 serves to clamp the base of the stirrup 40 against the inner face of the hub, there being a washer 18 between the head of the screw and the stirrup. The end portions of the stirrup lap the end wall of the mounting cup 3 upon the inner side of this wall while 45 the adjacent portion of the handle that is upon the exterior of the cup 3 also laps the end wall of this cup whereby the handle is confined to a fixed plane of rotation which is substantially parallel with the contact car- 50 rier 5 and the end wall 1 of the switch casing. The side portions 16' of the stirrup 16 extend along the common axis of the handle and the casing wall 2, these stirrup side portions being 55 slidingly received within notches 19 which are formed upon the inner side of a ring or body of insulation 20 which constitutes the contact carrier that is within the casing and which is to be moved to bring the contacts thereon into and out of engagement 60 with the contact parts 7. A plurality of electrically connected current conducting metallic spring barrels 21 are fixed upon the movable contact carrier 20 and project therefrom toward the opposite casing wall or contact 65 carrier 5. Metallic contacts 22 which are

complemental to the contacts upon the wall or carrier 5 are respectively assembled with the spring barrels 21 and are in current conducting and sliding or telescopic engagement therewith. Springs 23 are provided with 70 said spring barrels and press thereupon longitudinally thereof and upon the aforesaid complemental contacts 22 whereby said complemental contacts are placed into position to be engageable with the stationary contacts 75 upon the carrier 5 and the contact carrier 20 is pressed against the casing end wall 1 which serves as an abutment to limit the extent to which carrier 20 may be outwardly moved and which abutment confines this carrier to 80 a substantially fixed plane of rotation. The carrier 20 is thus not required to move along the axis of the handle and is, therefore, not liable to tilt or warp during the operation of the switch, the contacts 22 being guided in 85 their bodily movements only by the spring barrels respectively individual thereto and whose axes are maintained substantially parallel with the axis of the handle. The spring barrels being metallic, and the contacts 22 90 having current conducting engagement therewith, said contacts may be brought into electrical connection with each other by means of a metallic plate 24 which is desirably in the form of a ring that is held in fixed assembly 95 with the insulating ring 20 by the stems 25 of the spring barrels.

In the construction shown in Figs. 1, 2 and 4, the spring barrels are in the form of castings and have annular grooves between the 100 spring receiving body portions of the barrels and the stems of the barrels, these grooves being formed by means of the annular shoulders 26 which are spaced apart from the body portions of the barrels. The metallic plate 24 is formed with holes therethrough through which the stems 25 are passed, the portions of said plate which margin the holes through the plate being tightly received in the grooves between the shoulders 26 and 105 the bodies of the barrels. The carrier 20 is also formed with holes 27 which have enlargements 28 and 29 whereby annular shoulders 30 are left. The outer ends of the stems 25, which are hollow, are expanded within 110 the hole enlargements 29, by a riveting operation which serves to draw the shoulders 26 toward the shoulders 30 and to bring the plate 24 tightly against the inner face of the contact carrying ring 20. The various 115 spring pressed contacts 22 are effectively electrically connected by reason of their sliding engagement with their spring barrels respectively complemental thereto and the connection of these spring barrels by the metallic plate 24.

In the construction illustrated in Figs. 5 and 6, the spring barrels are formed into shape instead of being cast, the plate 24 being gripped between the bodies of the 120

spring barrels and the beads 26' that are formed upon the barrel stems 25'. The outer ends of the barrel stems are expanded into the contact carrier 20' and in a manner to bring the beads 26' against the shoulders 30' which result from the formation of holes 27' through the carrier 20' and the enlargements 28' of these holes.

Changes may be made without departing 10 from the invention.

Having thus described my invention, I claim:

1. In an electric switch, the combination with a casing having two opposite end walls; 15 of contacts carried by one of said end walls and exposed within the casing for engagement and constructed for the electrical connection therewith of circuit wires led to the casing; a handle upon the exterior of the casing and mounted to turn at the other casing end wall in a plane substantially parallel therewith; a contact carrier within the casing and coupled with the handle to be turned thereby, this contact carrier being 20 held from outward movement by the latter casing end wall; a plurality of current conducting spring barrels fixed upon said contact carrier and projecting therefrom toward the casing end wall that carries the aforesaid contacts, said contact carrier being inclusive of a metallic plate having holes formed therethrough and said spring barrels being formed with annular grooves in which the portions of said plate margining said holes are tightly received, whereby said barrels are electrically connected; contacts complementary to the aforesaid contacts, said spring barrels each having one of these complementary contacts in current conducting and sliding engagement therewith; and springs within said spring barrels and pressing thereupon longitudinally thereof and upon said contacts, said contacts being inclusive of a body of insulation that is interposed between the aforesaid plate and the casing end wall at which the handle is disposed.

2. In an electric switch, the combination with a casing having two opposite end walls; 25 of contacts carried by one of said end walls and exposed within the casing for engagement and constructed for the electrical connection therewith of circuit wires led to the casing; a handle upon the exterior of the casing and mounted to turn at the other casing end wall in a plane substantially parallel therewith; a contact carrier within the casing and coupled with the handle to be turned thereby, this contact carrier being held from outward movement by the latter casing end wall; a plurality of current conducting spring barrels fixed upon said contact carrier and projecting therefrom toward the casing end wall that carries the aforesaid contacts, said contact carrier being inclusive of a body of insulation, said spring barrels having continuations that enter said insulation body and are clinched into assembly therewith; contacts complementary to the aforesaid contacts, said spring barrels each having one of these complementary contacts in current conducting and sliding engagement therewith; and springs within said spring barrels and pressing thereupon longitudinally thereof and upon said contacts, whereby said complementary contacts are placed in position to be engageable with the first aforesaid contacts and said contact carrier is pressed against the casing end wall at which the handle is disposed.

3. In an electric switch, the combination with a casing having two opposite end walls; 30 of contacts carried by one of said end walls and exposed within the casing for engagement and constructed for the electrical connection therewith of circuit wires led to the casing; a handle upon the exterior of the casing and mounted to turn at the other casing end wall in a plane substantially parallel therewith; a contact carrier within the cas-

ing and coupled with the handle to be turned thereby, this contact carrier being held from outward movement by the latter casing end wall; a plurality of current conducting spring barrels fixed upon said contact carrier 70 and projecting therefrom toward the casing end wall that carries the aforesaid contacts, said contact carrier being inclusive of a metallic plate having holes formed therethrough and said spring barrels being 75 formed with annular grooves in which the portions of said plate margining said holes are tightly received, whereby said barrels are electrically connected; contacts complementary to the aforesaid contacts, said spring barrels each having one of these complementary contacts in current conducting and sliding engagement therewith; and springs within said spring barrels and pressing thereupon longitudinally thereof and upon said contacts, whereby said complementary contacts are placed in position to be engageable with the first aforesaid contacts and said contact carrier is pressed against the casing end wall at which the handle is disposed.

4. In an electric switch, the combination with a casing having two opposite end walls; 80 of contacts carried by one of said end walls and exposed within the casing for engagement and constructed for the electrical connection therewith of circuit wires led to the casing; a handle upon the exterior of the casing and mounted to turn at the other casing end wall in a plane substantially parallel therewith; a contact carrier within the casing and coupled with the handle to be turned thereby, this contact carrier being held from outward movement by the latter casing end wall; a plurality of current conducting spring barrels fixed upon said contact carrier and projecting therefrom toward the casing end wall that carries the aforesaid contacts, said contact carrier being inclusive of a body of insulation, said spring barrels having continuations that enter said insulation body and are clinched into assembly therewith; electrically connected contacts complementary to the aforesaid contacts, said spring barrels each having one of these complementary contacts in sliding engagement therewith; and springs within said spring barrels and pressing thereupon longitudinally thereof and upon said contacts, whereby said complementary contacts are placed in position to be engageable with the first aforesaid contacts and said contact carrier is pressed against the casing end wall at which the handle is disposed.

5. In an electric switch, the combination with a casing having two opposite end walls; 85 of contacts carried by one of said end walls and exposed within the casing for engagement and constructed for the electrical connection therewith of circuit wires led to the casing; a handle upon the exterior of the cas-

ing and mounted to turn at the other casing end wall in a plane substantially parallel therewith; a contact carrier within the casing and coupled with the handle to be turned thereby, this contact carrier being held from outward movement by the latter casing end wall; a plurality of current conducting spring barrels fixed upon said contact carrier and projecting therefrom toward the casing end wall that carries the aforesaid contacts, said contact carrier being inclusive of a metallic plate, said spring barrels being formed with grooves in which portions of said plate are tightly received, whereby said barrels are electrically connected, said contact carrier also being inclusive of a body of insulation that is interposed between the aforesaid plate and the casing end wall at which the handle is disposed, said spring barrels having continuations that enter said insulating body and are clinched into assembly therewith; contacts complementary to the aforesaid contacts, said spring barrels each having one of these complementary contacts in current conducting and sliding engagement therewith; and springs within said spring barrels and pressing thereupon longitudinally thereof and upon said complementary contacts, whereby said complementary contacts are placed in position to be engageable with the first aforesaid contacts and said contact carrier is pressed against the casing end wall at which the handle is disposed.

5. In an electric switch, the combination with a casing having two opposite end walls; of contacts carried by one of said end walls and exposed within the casing for engagement and constructed for the electrical connection therewith of circuit wires led to the casing; a handle upon the exterior of the casing and mounted to turn at the other casing end wall in a plane substantially parallel therewith; a contact carrier within the casing and coupled with the handle to be turned thereby, this contact carrier being held from outward movement by the latter casing end wall; a plurality of current conducting spring barrels fixed upon said contact carrier and projecting therefrom toward the casing end wall that carries the aforesaid contacts, said contact carrier being inclusive of a metallic plate, said spring barrels being formed with grooves in which portions of said plate are tightly received, whereby said barrels are electrically connected; contacts complementary to the aforesaid contacts, said spring barrels each having one of these complementary contacts in current conducting and sliding engagement therewith; and springs within said spring barrels and pressing thereupon longitudinally thereof and upon said complementary contacts, whereby said complementary contacts are placed in position to be engageable with the first aforesaid contacts and said contact carrier is pressed against the casing end wall at which the handle is disposed.

6. In an electric switch, the combination with a stationary contact carrier and a movable contact carrier, said carriers having opposing faces; of contacts upon the stationary carrier and exposed for engagement at the face thereof which is opposite the movable carrier and constructed for the electrical connection therewith of circuit wires; a plurality of spring barrels fixed upon said movable contact carrier and projecting therefrom toward the other contact carrier, said movable contact carrier being inclusive of a body of insulation, said spring barrels having continuations that enter said insulating body and are clinched into assembly therewith; electrically connected contacts complementary to the aforesaid contacts, said spring barrels each having one of these complementary contacts in sliding engagement therewith; springs within said spring barrels and pressing thereupon longitudinally thereof and upon said complementary contacts; and an abutment against which said springs also press the movable contact carrier.

7. In an electric switch, the combination with a stationary contact carrier and a movable contact carrier, said carriers having opposing faces; of contacts upon the stationary carrier and exposed for engagement at the face thereof which is opposite the movable carrier and constructed for the electrical connection therewith of circuit wires; a plurality of current conducting spring barrels fixed upon said movable contact carrier and projecting therefrom toward the other contact carrier, said movable contact carrier being inclusive of a metallic plate having holes formed therethrough and said spring barrels being formed with annular grooves in which the portions of said plate margining said holes are tightly received, whereby said barrels are electrically connected; contacts complementary to the aforesaid contacts, said spring barrels each having one of these complementary contacts in current conducting and sliding engagement therewith; springs within said spring barrels and pressing thereupon longitudinally thereof and upon said complementary contacts; and an abutment against which said springs also press the movable contact carrier, said movable contact carrier also being inclusive of a body of insulation that is interposed between the aforesaid plate and abutment, said spring barrels having continuations that enter said insulating body and are clinched into assembly therewith.

In witness whereof, I hereunto subscribe my name.

HARRY A. DOUGLAS.

able with the first aforesaid contacts and said contact carrier is pressed against the casing end wall at which the handle is disposed. 65

6. In an electric switch, the combination with a stationary contact carrier and a movable contact carrier, said carriers having opposing faces; of contacts upon the stationary carrier and exposed for engagement at the face thereof which is opposite the movable carrier and constructed for the electrical connection therewith of circuit wires; a plurality of spring barrels fixed upon said movable contact carrier and projecting therefrom toward the other contact carrier, said movable contact carrier being inclusive of a body of insulation, said spring barrels having continuations that enter said insulating body 80 and are clinched into assembly therewith; electrically connected contacts complementary to the aforesaid contacts, said spring barrels each having one of these complementary contacts in sliding engagement therewith; springs within said spring barrels and pressing thereupon longitudinally thereof and upon said complementary contacts; and an abutment against which said springs also press the movable contact carrier. 85

7. In an electric switch, the combination with a stationary contact carrier and a movable contact carrier, said carriers having opposing faces; of contacts upon the stationary carrier and exposed for engagement at the face thereof which is opposite the movable carrier and constructed for the electrical connection therewith of circuit wires; a plurality of current conducting spring barrels fixed upon said movable contact carrier and projecting therefrom toward the other contact carrier, said movable contact carrier being inclusive of a metallic plate having holes formed therethrough and said spring barrels being formed with annular grooves 100 in which the portions of said plate margining said holes are tightly received, whereby said barrels are electrically connected; contacts complementary to the aforesaid contacts, said spring barrels each having one of these complementary contacts in current conducting and sliding engagement therewith; springs within said spring barrels and pressing thereupon longitudinally thereof and upon said complementary contacts; and an abutment against 105 which said springs also press the movable contact carrier, said movable contact carrier also being inclusive of a body of insulation that is interposed between the aforesaid plate and abutment, said spring barrels having continuations that enter said insulating body and are clinched into assembly therewith. 110
